(57) **CLAIM**

The ornamental design for a saddlebag lid speaker housing for a motorcycle, as shown and described.

DESCRIPTION

FIG. 1 is a right front perspective view of a saddlebag lid speaker housing for a motorcycle according to the present invention;

FIG. 2 is a top plan view thereof;

FIG. 3 is a right side elevational view thereof;

FIG. 4 is a left side elevational view thereof;

FIG. 5 is a bottom plan view thereof and includes an audio speaker and a latch mechanism which are shown in broken lines and form no part of the claimed design;

FIG. 6 is a front elevational view thereof; and,

FIG. 7 is a rear elevational view thereof.

The broken lines in the figures are included for the purpose of illustrating portions of the saddlebag lid speaker housing that form no part of the claimed design.
